US0D1079568S

(12) **United States Design Patent** (10) **Patent No.:** **US D1,079,568 S**
(45) **Date of Patent:** **** Jun. 17, 2025**

(54) **FRONT AIR DIFFUSER FOR MOTOR VEHICLE**

(71) Applicant: **Dr. Ing. h.c. F. Porsche Aktiengesellschaft**, Stuttgart (DE)

(72) Inventor: **Emiel Burki**, Stuttgart (DE)

(73) Assignee: **Dr. Ing. h.c. F. Porsche Aktiengesellschaft** (DE)

(**) Term: **15 Years**

(21) Appl. No.: **29/893,515**

(22) Filed: **May 31, 2023**

(30) **Foreign Application Priority Data**

Feb. 21, 2023 (EM) 015011986-0007

(51) **LOC (15) Cl.** **12-16**

(52) **U.S. Cl.**

USPC **D12/169**
